UNITED STATES PATENT OFFICE.

WILLIAM DEATS, OF YONKERS, NEW YORK, ASSIGNOR TO OTIS ELEVATOR COMPANY,
OF JERSEY CITY, NEW JERSEY, A CORPORATION OF NEW JERSEY.

ELECTRICAL-CONTACT GOVERNOR.

1,148,295.

Specification of Letters Patent. Patented July 27, 1915.

Application filed February 12, 1910. Serial No. 543,604.

To all whom it may concern:

Be it known that I, WILLIAM DEATS, a citizen of the United States, residing at Yonkers, in the county of Westchester and 5 State of New York, have invented a new and useful Improvement in Electrical-Contact Governors, of which the following is a specification.

My invention relates to a centrifugal governor, more particularly designated and 10 designed for the operation of electrical contacts by centrifugal means.

One of the objects of my invention is to provide means for closing electric circuit 15 or circuits by the centrifugal action of a fly-ball governor.

Another object is to provide means dependent upon the change of rotative speed 20 of the governor for effecting step-by-step action at pre-determined speeds.

For the attainment of these ends and the accomplishment of other new and useful objects, my invention consists of the features of novelty in the construction, combination 25 and arrangement of the several parts hereinafter more completely described and claimed in the appended claims.

Referring to the drawings, Figure 1 is a part sectional elevation of my governor. 30 Fig. 2 is a diagrammatic representation of my invention as employed in conjunction with a motor.

Referring now more particularly to Fig. 1, the governor shaft 4 of the governor G 35 is rotatably held by the support 5 which is secured in any suitable manner, as for example, to the bearing hub 6. The bevel gears 7 and 8 are secured to the governor shaft 4 and the driving shaft 9, respectively, 40 thereby effecting the rotation of the governor shaft 4 whenever the driving shaft 9 is rotated. The contact arms 10 and 11 are secured to the governor shaft 4 in such a manner as to permit of the outward movement 45 of the said arms and to prevent any longitudinal movement of the same along the governor shaft. The stop collar 12 is secured to the governor shaft 4 and provides a limit stop for the latch collar 13 which is free to rotate about the governor shaft. 50

The levers 14 and 16 are pivoted to the contact arms 10 and 11, respectively, and are provided with the fly-balls 17 upon their outer arms and with the latches 18 upon 55 their inner arms. These latches 18 are

adapted to engage the latch collar 13. Attached to these levers 14 and 16 are the threaded eye-bolts 19 which pass through a portion of the arms 10 and 11 and which are surrounded by the coil springs 20. These 60 coil springs 20 are retained in position by the lock-nuts 21 and are adapted to exert a pressure upon the levers 14 and 16 such that the latches 18 are ordinarily held in engagement with the latch collar 13. These 65 coil springs may be and preferably are of different strength so that an upward pressure exerted by them upon their respective levers, is different, thus permitting one lever to be thrown out of engagement with 70 the latch collar without affecting the engagement of any other lever.

The lower portions of the arms 10 and 11 are provided with contacts 33, 34, 35, 36 which are secured to and insulated from the 75 said contact arms in any suitable and well known manner. A contact base 22 is also secured to the governor shaft 4 and rotates therewith. This contact base 22 is provided with concentric rings 23, 24, 25, 26, 27 80 and 28, suitably insulated from the base 22 and from each other. The contact base also supports contact carriers 29 and 30 which are provided with swivel mounted contacts 31 and 32 respectively. These said contact 85 carriers 29 and 30 are so arranged with respect to the contact arms 10 and 11 that when the contact arms move outwardly, the contacts 33, 34 and 35, 36, carried by the arms, engage with the said contacts 31 and 90 32. Connection is made between the contacts 33, 34, 35 and 36 of the contact arms 10 and 11 and the concentric contact rings by the flexible conductors 37. Electrical connection is also made between the swivel 95 mounted contacts 31 and 32 and the concentric contact rings 23 and 24 respectively by means of the contact carriers 29 and 30 and the bolts 54 and 55.

A series of fixed contacts 38, 39, 40, 41, 100 42 and 43 are provided and suitably located to make electrical connection with the concentric contact rings, and the terminals 44 are adapted to provide for electrical connection with the said fixed contacts. 105

In order that the operation of my invention may be more readily understood, it is necessary only to add that the rotation of the governor shaft 4 will cause the contact arms 10 and 11, and the base 22, to be ro- 110

- tated. The centrifugal action of the fly-balls 17 becomes greater as the rotative speed of the governor increases, finally becoming sufficiently great to overcome the 5 pressure of one of the springs 20, thereby causing one of the latches 18 to be disengaged from the latch collar 13 and allowing the corresponding contact arm to move outwardly until the contacts carried thereby 10 make connection with the contact 31 or 32.
- As the speed of rotation of the governor shaft 4 is further increased, the other contact arm may be thrown outwardly in a similar manner, making connections by 15 means of its respective contacts. It is to be here noticed that although but two contact arms are shown in Fig. 1, any desired number may be employed and by varying the strength of the retaining springs the points 20 of operation may be varied between any desired limits. Furthermore, it is not necessary that the arms be released in pairs as the action of each arm is entirely independent of any of the others.
- 25 In the stopping action of the governor, the contact arm last thrown out will be the first to return to its unoperated position. This is automatically effected by means of the beveled edges 45 and 46 of the latch collar 13 and the latch 18 respectively, and by means of the compression spring 47 which permits a slight give or upward movement of the latch collar 13 when the beveled faces come in contact. At the time, or before 30 the governor has reached a stop position, all of the contact arms will be in their original unoperated position with their latches 18 all engaged by the latch collar 13 and ready for immediate action.
- 35 An embodiment of my invention is shown by Fig. 2 in which my governor is employed to effect the acceleration of the motor M. In this exemplification there is shown a main switch S, acceleration magnets B and 40 C, a sectional resistance R and the necessary circuit connections. The motor M is provided with the slip rings 50 and the governor G is attached to the hub 6 of the motor and rotated by means of the motor shaft 45 and the bevel gears 8 and 7.
- 45 As soon as the main switch S is closed, the winding of the magnet B is energized and the contacts 48, 49, controlled thereby, effect a completion of an energizing circuit 50 to the motor M. Under the starting conditions all the sectional resistance R is in circuit with the motor M by way of the slip rings 50. Immediately after the closing of the contacts 48 and 49, the magnet C is energized and the contacts 51, 52 and 53 controlled thereby, are joined, thus short-circuiting a portion of the sectional resistance R. By this time the motor has started and 55 is rotating the governor G. As the speed of the motor and the governor increases, the

contacts 31, 33, and 34 are joined, thereby short-circuiting another portion of the sectional resistance R and permitting a still further increase in the speed of the motor. This in turn effects the operation of the 70 governor device to unite the other contacts 32, 35 and 36, thereby short-circuiting the entire sectional resistance R. The concentric rings are not shown in this figure for the sake of simplicity. 75

Although I have thus described my invention as applied to a motor, it is obvious that it may readily be applied to other apparatus.

One of the special features of my invention is that there may be any desired number of actions at any predetermined speeds and that the use of such a device is very advantageous in the operation of electrical contacts in that a snap action of the contact arms is obtained at each step. Such operation is especially adaptable to the acceleration of electric motors. In addition, other apparatus may be set into action when the governor is at any predetermined speed, 80 independently of or in connection with the operation of the motor.

Another feature is that my invention may be applied in any place where there are revolving parts. This facility of operation 95 does not make it necessary to be applied to any particular place; although it may be applied to any class of motors it is especially adaptable to an alternating current motor where, for instance, it is desired to start 100 the motor as an induction motor and then, when it comes up to speed, to change over to a synchronous motor. I wish, therefore, not to be limited to the herein described construction, combination or arrangement 105 of my invention as it is evident that those skilled in the art may make various changes without departing from the spirit and scope of my invention.

What I claim and desire to secure by Letters Patent of the United States, is:—

1. In an electrical switch, the combination of a governor comprising weighted arms, means for driving the governor, contacts carried by the governor arms, contacts to coöperate with the governor contacts, means coöoperating with the governor arms to cause the contacts operatively to close in regular succession as the speed of the governor increases, and means for latching said governor arms against centrifugal movement until a predetermined governor speed is reached. 115

2. In an electrical contact device, the combination of a centrifugal governor having revolving arms, contacts carried by the arms, revolving contacts to coöperate with the contacts on the arms, latching mechanism for holding the contacts on the revolving arms out of engagement with the other contacts, 125 130

- and controlled by the centrifugal action of the governor arms to allow the contacts on the arms to engage with the coöperating contacts in regular succession during the acceleration of the governor.
3. In an electrical contact switch, the combination of a governor comprising a rotatable shaft, a base rotated by the shaft, contacts mounted on the base, centrifugally controlled governor arms, contacts on the arms coacting with the contacts on the base, a latch collar, latches associated with the governor arms and engaged by the collar to hold the coöperating contacts out of engagement, and means to cause the latches on the arms to be released from latch engagement in a predetermined succession as the rotative speed of the governor arms continues to increase.
4. A centrifugal contact governor comprising a rotatable shaft, means for rotating the shaft, a contact base and contact arms secured to the shaft, a latch collar mounted on the shaft, latch levers mounted on the contact arms engaged by the latch collar, fly-balls carried by the said levers, and resilient means for retaining the latch levers in engagement with the latch collar until the speed of the governor has attained a predetermined value.
5. A centrifugal electrical contact governor comprising a rotatable shaft, contact base and contact arms secured to the shaft, a latch collar mounted on the shaft, latch levers mounted on the contact arms engaged by the latch collar, fly-balls carried by the said levers, and resilient means of various strengths for different latch levers provisionally to retain the same in engagement with the latch collar.
6. A centrifugal governor comprising a rotatable shaft, means for rotating the shaft, a contact base and contact arms secured to the shaft, a latch collar mounted on the shaft, latch levers mounted on the contact arms engaged by the latch collar, fly-balls carried by the said levers and springs for retaining the latch levers in engagement with the latch collar until the centrifugal action of the fly-ball exerts a greater pull than that of its corresponding spring.
7. In an electrical contacting device, the combination of a rotatable shaft, a contact base and contact arms secured to the shaft, a latch collar mounted on the shaft, latch levers mounted on the contact arms and engaged by the latch collar, fly-balls carried by the said levers and operable at predetermined speeds to release the levers from the latch collar, resilient means for opposing the centrifugal action of the fly-balls and the contact arms, contacts carried by the said contact arms, and coöperative contacts carried by the contact base.
8. In a centrifugal contact device, the combination of a rotatable shaft, a contact base and contact arms secured to the shaft, electrical contacts carried by the contact arms, a latch collar mounted on the shaft, latch levers pivoted on the contact arms, fly-balls carried by the said levers, bolts fastened to the said levers and passing through openings on the arms, and coil springs surrounding the bolts tending to keep the latch levers in engagement with the latch collar.
9. In a centrifugal governor, an electrical contacting device, the combination of a rotatable shaft, a contact base and contact arms secured to the shaft, a latch collar mounted on the shaft, latch levers pivoted on the contact arms and engaging the collar, fly-balls carried by the said levers, and means resisting the centrifugal action of the fly-balls to different degrees to allow the latch levers successively to be disengaged from and reengaged with the latch collar independently of each other.
10. A centrifugal electrical contacting device comprising a rotatable shaft, a contact base and contact arms secured to the shaft, contacts on the contact arm, contacts on the contact base to coöperate with the contacts on the contact arms, a series of concentric contact rings secured to the contact base, electrical connection between the contacts on the contact arms and certain of the contact rings and between the contacts on the contact base and others of the rings, said contact arms being operable in a predetermined order whereby circuit connections are automatically closed in a predetermined manner through the said contact rings.
11. The combination of electrical switch contacts, means for rotating said contacts about a common axis, one of said contacts being movable by centrifugal force into engagement with the other contact, a latch holding said movable contact against such movement, and a weight carried by the latch and operable by centrifugal force to release said contact and permit such movement.
12. The combination of electrical switch contacts, means for rotating the contacts about a common axis, a latch holding the contacts separated, and a weight carried by the latch and operable by centrifugal force to release said latch.
13. The combination of a rotatable member, switch contacts carried thereby and rotatable therewith, one of said contacts being movable by centrifugal force into engagement with the other contact, a latch device preventing such movement, and a speed governor operable to release said latch.
14. The combination of a rotary member, a switch contact carried thereby, a second switch contact also carried by said member and movable radially thereof in engagement with said first-named contact, a device for locking said second contact against such ra-

dial movement, and means for automatically releasing said device when the speed of the rotary member reaches a predetermined value.

15. The combination of a member rotatable about a vertical axis, a switch arm pivoted to said member for movement about a horizontal axis, coöperating switch contacts carried by said arm and said rotatable member, a device for holding said arm against movement about its pivot, and means to automatically release the switch arm when the speed of said rotary member exceeds a predetermined value.
- 10 16. The combination of a rotary member, a switch arm carried thereby and movable relatively to said member, coöperating switch contacts carried by said arm and said member, a latch for holding said arm against such movement, and means operated by centrifugal force for releasing the latch and bringing said coöperating contacts together.
17. The combination of a member rotatable about a vertical axis, a switch arm connected thereto by a horizontal pivot, a latch carried by said member and holding the
- 20
- 25

switch arm from movement about its pivot, and a speed governor operable to release the latch.

18. The combination of a rotary member, 30 a switch carried thereby and comprising a switch arm pivoted to said member, and movable by centrifugal force into closed position, a catch for holding said switch arm in open position, and means to automatically 35 release the catch when the speed of said rotary member reaches a predetermined value.

19. The combination of a rotary member, a plurality of electrical switches carried thereby and operable by centrifugal force 40 into closed position, a device for latching the switches open, and means for automatically causing said switches to be released in succession as the speed of said rotary member reaches predetermined increasing values. 45

In testimony whereof, I have signed my name to this specification in the presence of two subscribing witnesses.

WILLIAM DEATS.
